United States Patent

Des. 238,113
Patented Dec. 16, 1975

238,113

TOOL BOX

Donald G. Hart, R.R. 1, Geneseo, Ill. 61254

Filed Nov. 8, 1973, Ser. No. 413,877

Term of patent 14 years

Int. Cl. D3—02

U.S. Cl. D87—1 R

FIG. 1

FIG. 2

FIG. 3

FIG. 4

FIG. 1 is a front elevational view of a tool box of this invention, with the rear being a mirror image of said front;

FIG. 2 is an end elevational view thereof, with the opposite end being identical herewith;

FIG. 3 is a top view thereof; and

FIG. 4 is a bottom view thereof.

I claim:

The ornamental design of a tool box, substantially as shown.
